CLAIM

The ornamental design for a housing for a blender, as shown and described.

DESCRIPTION

FIG. 1 is a top, front, right side perspective view of a housing for a blender showing our new design;

FIG. 2 is a front elevational view thereof;

FIG. 3 is a rear elevational view thereof;

FIG. 4 is a top plan view thereof; and,

FIG. 5 is a right side elevational view thereof, the left side being a mirror image of the right side.
